UNITED STATES PATENT OFFICE.

ERNEST A. GALLISON, OF PORTLAND, MAINE, ASSIGNOR TO COLONIAL FAST COLOR TIPPING COMPANY, OF KITTERY, MAINE, A CORPORATION OF MAINE.

MACHINE FOR TIPPING LACES.

1,030,513.

Specification of Letters Patent. Patented June 25, 1912.

Application filed June 12, 1911. Serial No. 632,736.

To all whom it may concern:

Be it known that I, ERNEST A. GALLISON, a citizen of the United States, and a resident of Portland, in the county of Cumberland and State of Maine, have invented 5 certain new and useful Improvements in Machines for Tipping Laces, of which the following is a specification.

This invention relates to a machine for 10 forming sheet material into a tube around a portion of the fabric of a lacing strip such as is used for shoe, corset and other laces.

The invention has for its object to provide 15 a machine especially adapted to form lacing tips from sheet material such as celluloid.

The invention is embodied in a machine adapted to sever blanks from a strip of 20 sheet celluloid and fold said blanks around portions of a lacing fabric in such manner as to convert each blank into a tube which closely embraces the fabric and is given a permanent form by the machine, means being 25 provided for severing the tube and the portion of the fabric embraced by it midway between the ends of the tube and thus forming ends of two tipped laces.

The invention consists in the improvements 30 which I will now proceed to describe and claim.

Of the accompanying drawings which form a part of this specification,—Figure 1 represents a side elevation of a machine embodying my invention; Fig. 2 represents a 35 longitudinal section of the same; Fig. 3 represents a fragmentary section on line 3—3 of Fig. 2; Fig. 4 represents a front end elevation; Fig. 5 represents a section on line 5—5 of Fig. 2; Fig. 6 represents a section on line 6—6 of Fig. 2; Fig. 7 represents a section on line 7—7 of Fig. 2; Fig. 8 represents a section on line 8—8 of Fig. 7. Fig. 9 represents a fragmentary elevation 45 showing the means for rotating the lower feed roll; Fig. 10 represents a top plan view of a portion of the machine including the carrier hereinafter referred to, and the fixed parts which support and guide the same; Fig. 11 represents a section on line 11—11 of Fig. 10; Fig. 12 represents a section on line 12—12 of Fig. 10; Fig. 13 represents a sectional detail hereinafter referred to; Figs. 14, 15 and 16 represent fragmentary sectional views illustrating

different parts or steps of the tip-forming operation; Fig. 17 represents a fragmentary sectional view representing the operation of severing a formed tube and the portion of the fabric embraced thereby; Fig. 18 60 represents a section on line 18—18 of Fig. 17; Fig. 19 represents a fragmentary perspective view showing a portion of the carrier top plate hereinafter described; Fig. 20 represents a fragmentary, perspective 65 view showing a portion of the slide herein-after described; Fig. 21 represents a view similar to a portion of Fig. 10 showing means for forming frusto-conical tips; Fig. 22 represents a plan view showing cutters 70 adapted to form parts of frusto-conical tips; Fig. 23 represents a view of a blank adapted to form two cylindrical tips; Fig. 24 represents a blank adapted to form two frusto-conical tips; Fig. 25 represents a 75 view of a tube applied to the lacing fabric and adapted to form two substantially cylindrical tips; Fig. 26 represents a view similar to Fig. 25 showing the tube adapted to form two frusto-conical or tapering tips. 80 Fig. 27 represents the forward end portion of the strip from which frusto-conical tips are formed; Fig. 28 represents a bottom end view of the secondary folding blade employed in making frusto-conical tips. 85

Similar reference characters indicate the same or similar parts in all the figures.

In the drawings,—25 represents a frame base having a horizontal bed 26 on which a strip 27 of sheet celluloid or other like pyroxylin material is moved intermittently by feed rolls 28, 29, rotated step-by-step, the bed having an opening 30 (Fig. 2) which receives the upper portion of the lower feed roll 28. 90

31 represents a sliding carrier which is reciprocated horizontally on guides on the base 25 toward and from the forward end 26' of the bed, said carrier being adapted to hold means for heating the tip-forming 100 devices hereinafter described.

As here shown, the carrier is a hollow box-like structure in which any suitable heater may be placed. I have here shown conventionally in side elevation an electric 105 heater 32. The carrier 31 supports and moves certain elements of the tip-forming mechanism hereinafter described which severs a tip blank 27^a from the strip 27, wraps said blank in tubular form around 110

the lacing fabric, welds the longitudinal edges of the blank together to provide a permanent tube 27^b which, as indicated by Fig. 21, is of double the length of a lacing tip, and severs said tube and the lacing fabric therein to form ends of two tipped laces.

The tip-forming mechanism includes elements supported above the carrier 31 by a frame standard 25^a, said standard being bolted to the base 25 and having bearings in which is journaled a cam shaft 34, one side of which is journaled in a bearing on a frame standard 25^b which is also bolted to the base. The shaft 34 is provided with a worm gear 35 meshing with a worm 36 on a transverse driving shaft 37 journaled in bearings on the standard 25^b. The shaft 34 is provided with a series of cams 38, 39, and 40 which actuate different parts of the tip-forming mechanism.

The cam 38 which causes the reciprocating movements of the carrier 31 has a groove 41 (Fig. 7) engaging a trundle roll 42 on a bar 43 which is movable in a guide in the standard 25^a and is provided with a rack 44 meshing with a gear segment 45 (Fig. 2) on a rock shaft 46 journaled in bearings on the base. Said rock shaft has an arm 47 which is connected by links 48 with an ear 49 on the carrier 31.

The cam 39 is formed to reciprocate a slide 50 carrying a shear blade 51 which cooperates with a shear blade 52 on the carrier in severing a blank from the strip 27, as shown by Fig. 14. The slide 50 also carries a primary folding blade 53 formed to cooperate with opposed faces on parts supported by the carrier 31 in imparting to the blank a trough shape (Fig. 14) preliminary to the application of the fabric to the blank. The cam 40 is formed to reciprocate a slide 54 which carries a secondary folding blade 55 which has a grooved face 56 adapted and operated as hereinafter described to first bend one of the edges of the trough shaped blank inwardly, as shown by Fig. 15, and afterward bend the opposite edge of the blank inwardly, as shown by Fig. 16, to complete the formation of the tube 27^b.

The slides 50 and 54 are reciprocated vertically in guides in the frame standard 25^a, and are located over the path in which the carrier 31 moves, so that the blades 51, 53 and 55 are adapted to cooperate with the parts of the tip-forming mechanism next described, mounted on the carrier. The shear blade 52 is formed by the intersection of the outer side and upper edge of a member or flange 58 (Figs. 1, 2, 6 and 14) on a horizontal top plate 59 rigidly attached to the carrier 31. The inner side 60 of the flange 58 forms one of the opposed faces between which the blank is bent to a trough shape (Fig. 14). The other of said faces is

the end 61 (Fig. 20) of a slide 62 which is movable horizontally on the top plate 59, the latter being provided with a guide way for said slide and with gibs 63 (Fig. 18) confining the slide in the guideway. The member 58 is rigidly attached to the carrier and moves in a fixed path therewith. The slide 62 moves with the carrier and has a limited movement independently thereof, so that the faces 60 and 61 constitute sides of a channel 64 (Fig. 14) of variable width. When the carrier is at the inward extreme of its movement, as indicated by Fig. 14, the channel is at its maximum width and is positioned to receive the lower portion of the folding blade 53, the shear blade 52 being positioned to cooperate with the reciprocating shear blade 51. The carrier is held in this position while the slide 50 descends and causes the severance of a blank from the strip 27 by the shear blade, and the insertion of the blank in the channel 64 by the folding blade 53, the blank being given a trough shape by the sides of the channel and by the blade. The slide 50 then rises and the carrier is moved outwardly to the position shown by Fig. 15, the channel being now under the secondary folding blade 55, and the channel face 61 substantially in alignment with the outer side of said blade. While the carrier is in this position the operator deposits the portion of a lacing fabric around which the blank is to be wrapped, in the trough formed by the partly folded blank. The slide 50 then rises and the carrier is moved outwardly to the position shown by Fig. 16, the slide 62 and its face 61 being at this time arrested by a fixed stop 66 (Fig. 2) attached to the base 25 so that the face 61 remains in the position shown by Fig. 15. The last described movement of the carrier therefore moves the face 60 toward the face 61 and decreases the width of the channel 64, the face 60 being now substantially in alignment with the inner side of the secondary folding blade. The slide 54 now again descends and engages the other lip of the partially folded blank, rolling it over upon the previously rolled lip and completing the formation of the tube, as shown by Fig. 16.

Prior to each descent of the secondary folding blade 55, a small quantity of alcohol or other liquid which is a softener or solvent of celluloid is discharged upon the back of said blade, through a duct 67 (Figs. 4 and 6) in the frame standard 25^a, said duct com-

municating with a cup 68 which is intermittently charged with alcohol from a reservoir 69 by automatic means hereinafter described, the duct 67 being provided with a 5 needle valve 70 which is opened by the ascent of the blade 55, and allows the charge in the cup 68, or a portion thereof, to fall upon the upper edge of the blade, from which it flows downwardly upon the sides of the 10 blade to its lower edge. The quantity of alcohol thus supplied is sufficient to coat the entire lower edge of the blade 55, and soften the portions of the blank with which said edge comes in contact. This softening of the 15 tip material, together with the pressure exerted upon it by the secondary folding blade, and the heat imparted to the faces 60 and 61, as well as to the blade 55 by the heater, insures the formation of a permanent tube 20 27^b which closely embraces the inclosed portion of the lacing fabric.

As mentioned, the solvent is so applied as to coat the entire lower edge of the blade 55. Therefore when said blade descends, it 25 causes the solvent to permeate the entire mass of the bunched lacing fabric, and to act on the entire inner surface of the celluloid envelop so that the heat, and the pressure of the final act of wrapping, results in 30 the inner surface portions of the sheath, uniting with the fibers of the lacing fabric with such intimacy as to hold the tip tightly on the fabric when in use, without any necessity of punching or otherwise rendering the 35 sheath irregular. Moreover the over-wrapped edges or lips also intimately unite so that the final sheath is practically seamless or integral throughout, and capable of 40 withstanding the effort of the fabric to expand from a condition of extremely compressed and small cylindrical form.

The tube 27^b and the inclosed fabric are next severed transversely at the center of the length of the tube to form tipped ends of 45 two laces, by a knife blade 72 having a notch, one end of which is sharpened to form a cutting edge 73.

The blade is attached to a shank 74 which is movable endwise in a guide (Fig. 18) in 50 the top plate 59, and is normally held in the position shown Fig. 2 by a spring 76 interposed between a shoulder 77 (Fig. 17) of the top plate, and a pin 78 on said shank. The spring holds one end of the blade 72 55 against a stop screw 79 on the slide 62 and projects the outer end of the shank 74 yielding from the outer end of the top plate 59, as shown by Fig. 2. The stop 79 causes the knife to move in unison with the slide 62 excepting when a stop 80 on an oscillatory arm (Fig. 7) is moved into the path of the shank 74, as shown by Fig. 17. The stop 80 is normally at one side of the path of the shank, as indicated by Fig. 7, and is moved 60 into and out of said path by means herein- 65

after described. The stop is held out of the path of the knife shank during the above described steps of the tip-forming operation, and is moved into the path of the shank 70 after the completion of the tube and before the carrier is moved to its extreme outward position represented by Fig. 2.

The movement of the carrier to the last-mentioned position when the stop 80 is in the path of the knife shank, causes the stop 75 to arrest the movement of the knife 72 in the same direction, so that the completed tube is forced by the face 60 against and across the cutting edge 73 of the knife, as shown by Fig. 17, the tube and the fabric 80 inclosed therein being thus severed, and two tipped lacing ends formed. The stop 80 is then moved out of the path of the knife shank and the knife is returned by the spring 85 to the position shown by Fig. 2, when the machine is in readiness for a repetition of the operations above described.

As indicated by Figs. 17, 18, 19 and 20, the top plate 59 and its flange 58 are provided with a slot 83 to receive and guide the 90 knife blade, while the slide 62 is provided with a slot 84 for the same purpose, said slots being in alinement with each other. The slide 62 is provided with a stud 83^a which projects into a slot 85, Figs. 10 and 95 12. The carrier top-plate 59 has a stop screw 84^a which projects into said slot and is adapted to bear on the stud 83^a and move the slide 62 with the carrier when the carrier is moving inward or toward the feed rolls. When the carrier is moving outward, or in the opposite direction, the slot 85 permits a limited movement of the carrier independently of the top-plate, the latter remaining stationary until the inner end of 100 the slot abuts against the stud 83^a, as indicated by dotted lines, Fig. 12. The spring 76 which retracts the severing knife, also acts through the heel of the knife and the stop 79 (against which said heel normally 105 bears, as shown by Fig. 2,) to force the slide 62 outward as far as the stop 84^a will permit, provision being thus made for yielding maintaining the channel 64 at the maximum width shown by Fig. 14. Provision is thus made for the varying relative 110 positions of the slide and the carrier, and therefore of the faces 60 and 61, shown by Figs. 14, 15, 16 and 17. The cam groove 41 is formed, as shown by Fig. 7, to impart the 115 above described movements to the carrier, said movements being step-by-step and the carrier being held stationary for a suitable period after each movement.

Adjustable stop screws 87 (Fig. 10) are 120 provided to limit the outward movement of the carrier, said stops being secured to the base 25 and arranged to abut against gibs 63 attached to the carrier top-plate. An adjustable stop rod 88 (Fig. 2) is adapted 130

to abut against the carrier lug 49 and limit the inward movement of the carrier, said rod having a threaded portion 89, which is engaged with the base 25. A jam nut 90 engaged with the portion 89 and bearing against the base confines the stop rod 88 in any position to which it may be adjusted.

The connection between the links 48 with the carrier lug 49 is adjustable to enable the limit of the inward movement of the carrier to be varied to the extent required to insure an exact position of the lower shear blade 52 with relation to the upper shear blade 51. To this end, the lug 49 is provided with a cavity in which is fitted a block 91 (Fig. 13) through which passes the pin 92 which connects the links 48 with the lug 49. The lug 49 is also provided with studs having screw-threaded portions 93 engaged with the threaded sockets in the lower portion of the arm and eccentric portions 94 bearing on opposite sides of the block. By rotating the studs, the eccentric portions 94 are shifted laterally and slightly vary the position of the lug 49 relatively to the pin 92. The lug 49 is provided with a slot 95 through which the pin 92 passes.

The arm 81, carrying the knife-operating stop 80, is attached to a rock shaft 96 (Figs. 30 7 and 8) journaled in bearings on the base 25. Said rock shaft is provided with a bent arm 97 (Figs. 1 and 7) having a trundle roll 98 at its outer end adapted to be engaged by a projection 99 on the cam 38, said projection being preferably a resilient spring arm having a shank 100 secured to one side of the cam 38, as indicated by Fig. 7. A spring 101 (Fig. 8) attached at one end to the rock shaft 96, and at the other end to the base 25, holds the rock shaft and its arms 81 and 97 normally in the position shown by Fig. 7, the stop 80 being out of the path of the knife shank 74, and the trundle roll 98 in the path of the projection 99.

When the rotation of the cam 38 brings the cam projection 99 to the trundle roll 98, the arm 97 is moved by said projection and turns the rock shaft 96 sufficiently to move the stop 80 into the path of the shank 74, thus causing the above described operation of the knife.

The reservoir 69, containing a supply of alcohol, is provided with an outlet 102 (Fig. 4) which includes a casing 103 containing a valve adapted to be oscillated on a vertical axis, and to alternately open and close the outlet, the delivering end of which coincides with the cup 68. The stem of the valve is provided with an arm 104 which is adapted to be oscillated to open and close the valve, and is normally held by a spring 105 in position to close the valve. The hub of the cam 40 is provided with cam wings 106 and 107 which are separated from each

other, as shown by Fig. 4, and are adapted to act on the arm 104 at different times during a complete rotation of the shaft 34 and move said arm in the direction required to open the valve.

The above described mechanism is timed to supply alcohol to the cup 68 as required to insure the delivery of a charge of alcohol to the back of the secondary folder 55 during each upward movement of said folder.

The preferred form of the cam 39 is that shown by Fig. 5, said cam having a concentric portion occupying the greater part of its perimeter and a short cam groove 39^a which engages a trundle roll 50^a on the slide 50, and is formed to impart the described movements to the upper shear blade 51 and the primary folding blade 53.

The preferred form of the cam 40 is that shown by Fig. 6, said cam having two cam grooves 40^a and 40^b which coöperate with a trundle roll 54^a on the slide 54, in imparting the above described movements to the secondary folding blade 55.

The lower feed roll 28 is reciprocated step-by-step by suitable mechanism, preferably that shown by Figs. 2, 3 and 9, said mechanism comprising a connecting rod 108 engaged at one end with the carrier, a lever 109 engaged with the opposite end of the rod 108 and mounted to oscillate on the shaft 110 of the lower feed roll, a pair of pawls 111, 112 pivoted to the lever 109, and a ratchet 113 attached to the feed roll 28. The rod 108 is reciprocated by the movements of the carrier 31 and oscillates the lever 109 which in turn reciprocates the pawls 111, 112 and causes them to impart step-by-step rotary movements to the feed roll 28.

A shield 114 mounted on an arm 115 which is pivoted on the shaft 110 is adapted to vary the operative movements of the pawls so that feed movements of any desired extent may be imparted to the roll 28. The shield may be adjusted by means of a rod 116 connected with the arm 115 and adapted to turn the latter in either direction on the shaft 110. The upper feed roll 29 is mounted in yielding bearings which are pressed downwardly by springs, as shown by Fig. 3, so that the upper roll is pressed yieldingly against the strip 27 interposed between it and the lower roll, the two feed rolls being connected by gears 121, 122, (Fig. 3).

The upper shear blade 51 and the lower shear blade 52 above described are adapted to form a rectangular blank 27^a of the form shown by Fig. 23, this blank forming a cylindrical tube 27^b, as shown by Fig. 25.

The driving shaft 37 is preferably driven by a belt running on a pulley 117, said pulley being loose on the shaft and adapted to be connected therewith by a clutch 118 con-

trolled by a treadle (not shown) through a rod 119 and a bell crank 120 (Fig. 4).

When the tube is to be given a double frusto-conical form, as shown by Fig. 26, 5 an upper shear blade 51^a of the form shown by Fig. 22 is employed, said blade having two obtuse angle cutting edges 51^b and 51^c formed by the intersection of its sides with its bottom end. The lower shear blade 10 which is represented by 52^a (Fig. 21) is recessed to cooperate with the cutting edge 51^b.

In the embodiment of this invention, the portion 26' of the bed which supports the 15 strip 27 is utilized as a cutting edge 52^c (Fig. 22), which is recessed to coöperate with the cutting edge 51^c. At each descent of the upper shear blade 51^a the cutting edges 51^c and 52^c form an angular edge 27^c 20 and the cutting edges 51^b and 52^a form an angular edge 27^d. The feed movement of the strip 27 is longer than is the case when a blank with parallel edges is formed, the edge 27^c, which is the forward end of the 25 strip, being advanced by each feed movement a distance equal to the width of the blank plus the thickness of the shear blade 51^a, so that a portion of the strip between each blank and the next becomes waste material as indicated by dotted lines, Fig. 27. The acting edge or end of the secondary folding blade 55 used in making frusto-conical tips is formed as shown by Fig. 28.

The stop screws 66 and 87 enable the 35 limits of the outward movements of the carrier 81 and of the slide 62 to be adjusted independently to vary the width of the channel 64, and enable tips of different diameters to be formed. When the machine is adjusted to change the diameter of the tips, 40 the secondary folding blade 55, previously used, will be removed, and another blade of greater or less thickness substituted for it, according as the diameter is to be increased 45 or decreased.

It is obvious that any suitable flexible material may be employed for the lacing tips, and while I prefer a pyroxylin material such as celluloid, other or equivalent flexible 50 sheet material may be used. The recently invented material known as "celum" which is analogous to celluloid but is relatively non-combustible, may be employed.

By the term celluloid employed herein, I 55 do not mean to restrict myself to any one species of pyroxylin as the material employed, although at present I consider celluloid as the best substance for the purpose.

Any material in sheet form and capable of 60 being cut to form the blanks and then folded or wrapped around the lacing fabric, while its inner surface is so softened as to be united to the fabric by pressure, and to have its contacting edges so combined as to leave 65 the sheath or wrapping practically seamless,

is to be understood as included by the term celluloid.

I claim:

1. A lacing tipping machine comprising opposed faces forming the sides of a channel, means coöperating therewith for first forming a tip blank into a trough adapted to receive a portion of a lacing fabric and then bending the edges of the blank successively to form a tube embracing the fabric, 70 one of said edges overlapping the other, and means for heating said faces.

2. A lacing tipping machine comprising opposed faces forming the sides of a channel, means coöperating therewith for first 80 forming a tip blank into a trough adapted to receive a portion of a lacing fabric and then bending the edges of the blank successively to form a tube embracing the fabric, one of said edges overlapping the other, and means 85 for applying a liquid solvent to the blank during the edge bending operation.

3. A lace tipping machine comprising opposed faces forming the sides of a channel, means coöperating therewith for first 90 forming a tip blank into a trough adapted to receive a portion of a lacing fabric and then bending the edges of the blank successively to form a tube embracing the fabric, one of said edges overlapping the other, the 95 edge-bending means including a folding blade and means for applying a liquid solvent to said blade.

4. A lace tipping machine comprising 100 opposed members having faces forming the sides of a channel, means independent of said members but coöperating with said faces for first forming a tip blank into a trough adapted to receive a portion of a lacing fabric and additional means for bending 105 the edges of the blank successively to form a tube embracing the fabric, said additional bending means being structurally independent of the channel forming members.

5. A lace tipping machine comprising, 110 in combination, a primary folding blade, a carrier having opposed faces forming a channel, a secondary folding blade, both of said blades being structurally independent of the carrier and said faces and movable in planes substantially perpendicular to the plane of said carrier, and mechanism for operating said parts to first cause the primary folding blade to coöperate with the channel faces in forming a blank of sheet 115 material into a trough adapted to receive a portion of a lacing fabric, then causing the secondary blade to coöperate with the channel faces in bending the edges of the blank inwardly to form a tube embracing the 120 fabric.

6. A lace tipping machine comprising, in combination, a primary folding blade, a carrier having opposed faces forming a channel, a secondary folding blade, and 130

mechanism for operating said parts to first cause the primary folding blade to coöperate with the channel faces in forming a blank sheet material into a trough adapted to receive a portion of a lacing fabric, then causing the secondary blade to coöperate with the channel faces in successively bending the edges of the blank inwardly to form a tube embracing the fabric, one of said edges overlapping the other, the carrier being provided with a heater adapted to heat the said faces.

7. A lace tipping machine comprising, in combination, a primary folding blade, a carrier having opposed faces forming a channel, a secondary folding blade, and mechanism for operating said parts to first cause the primary folding blade to coöperate with the channel faces in forming a blank of sheet material into a trough adapted to receive a portion of a lacing fabric, then causing the secondary blade to coöperate with the channel faces in successively bending the edges of the blank inwardly to form a tube embracing the fabric, one of said edges overlapping the other, means being provided for applying a liquid solvent to the secondary folding blade.

8. A lace tipping machine comprising, in combination, a primary folding blade, a carrier having opposed faces forming a channel, a secondary folding blade, both of said blades being structurally independent of the carrier and movable in planes substantially perpendicular to the plane of said carrier, a severing knife movable crosswise of the channel, and mechanism for operating said parts to first cause the primary folding blade to coöperate with the channel faces in forming a blank of sheet material into a trough adapted to receive a portion of a lacing fabric, then causing the secondary blade to coöperate with the channel faces in successively bending the edges of the blank inwardly to form a tube embracing the fabric, and finally causing the knife to transversely sever the tube and the portion of the fabric embraced thereby.

9. A lace tipping machine comprising means for horizontally feeding a strip of sheet material, and mechanism for severing a blank from said strip and folding the same by successive operations around a lacing fabric to form a tube, said mechanism including a horizontally reciprocable carrier supporting parts of the tube forming mechanism, independent vertically movable slides supporting other parts of said mechanism, means for reciprocating the carrier, said means having provisions for imparting to the carrier a step by step movement in one of its directions of movement, and means for independently reciprocating the said slides alternately and in conformity to the movements of the carrier.

10. A lace tipping machine comprising means for horizontally feeding a strip of sheet material, and mechanism for severing a blank from said strip and folding the same by successive operations around a lacing fabric to form a tube, said mechanism including a horizontally reciprocable carrier supporting parts of the tube forming mechanism, independent vertically movable slides supporting other parts of said mechanism, means for reciprocating the carrier, said means having provisions for imparting to the carrier a step by step movement in one of its directions of movement, means for independently reciprocating the said slides alternately and in conformity to the movements of the carrier, and means including a knife movable with and independently of the carrier for severing the tube and the fabric embraced thereby.

11. A lace tipping machine comprising means for horizontally feeding a strip of sheet material, and mechanism for severing a blank from said strip and folding the same by successive operations around a lacing fabric to form a tube, said mechanism including a horizontally reciprocable carrier supporting parts of the tube forming mechanism, and provided with means for heating the said parts, independent vertically movable slides supporting other parts of said mechanism, means for reciprocating the carrier, said means having provisions for imparting to the carrier a step by step movement in one of its directions of movement, and means for independently reciprocating the said slides alternately and in conformity to the movements of the carrier.

12. A lace tipping machine comprising means for horizontally feeding a strip of sheet material, mechanism for severing a blank from said strip and folding the same by successive operations around a lacing fabric to form a tube, said mechanism including means for partially folding the blank to form a trough, and a reciprocating folding blade adapted to roll the edges of the trough shaped blank inward, and means for applying a liquid solvent to said blade.

13. A lace tipping machine comprising means for horizontally feeding a strip of sheet material, mechanism for severing a blank from said strip and folding the same by successive operations around a lacing fabric to form a tube, said mechanism including means for partially folding the blank to form a trough, and a reciprocating folding blade adapted to roll the edges of the trough shaped blank inward, means for applying a liquid solvent to said blade, and means for severing the tube and the fabric inclosed therein.

14. A lace tipping machine comprising means for horizontally feeding a strip of sheet material, an upper shear blade, a pri-

mary folding blade connected therewith, a lower shear blade coöperating with the upper shear blade, movable opposed members having channel faces adapted to co-
5 operate with the primary folding blade in imparting a trough shape to the blank, a secondary folding blade adjacent to the primary folding blade and adapted to coöperate with the channel faces, said folding
10 blades being structurally independent of the said movable opposed members, means for shifting said movable opposed members in unison to carry said channel faces to position to alternately coöperate with said primary and secondary blades, and means for
15 operating said upper shear blade and folding blades.

15. A lace tipping machine comprising means for horizontally feeding a strip of sheet material, an upper shear blade and a primary folding blade connected therewith, mechanism for vertically reciprocating said blades across the path of the strip, a carrier having a lower shear blade adapted to co-
20 operate with the upper shear blade in severing a blank from the strip, and a channel, the sides of which are adapted to coöperate with the primary folding blade in imparting a trough shape to the blank, one face of
25 said channel being rigidly attached to the carrier, a slide which is movable with and independently of the carrier, and has an end face forming the opposite side of the channel whereby the width of the channel
30 may be varied, a secondary folding blade adjacent to the primary folding blade and movable independently thereof, mechanism for vertically reciprocating the secondary folding blade, to cause it to enter the channel and act on a partially folded blank
35 therein, mechanism for reciprocating the carrier horizontally, said mechanism having provisions for moving the carrier step by step in one direction, and for first holding
40 the lower shear blade and the channel in position to coöperate with the upper shear blade and primary folding blade respectively, then holding the channel in the path of the secondary folding blade with the
45 channel at its maximum width and one of its sides in alinement with one side of the secondary folding blade, and finally contracting the channel while it is in the path of the secondary folding blades, to bring its
50 opposite side into alinement with the opposite side of the secondary folding blade.

16. A lace tipping machine comprising means for horizontally feeding a strip of sheet material, an upper shear blade having two angular cutting edges, a primary folding blade connected therewith, a fixed bed having a fixed angular shear blade coöperating with one of the cutting edges of the upper shear blade, a lower angular shear blade coöperating with the other cutting edge of the upper shear blade, movable opposed members having channel faces which are angular and formed to produce frusto-conical tips, said faces being adapted to coöperate with the primary folding blade in imparting a trough shape to the blank, an independent secondary folding blade adjacent to the primary folding blade and formed to coöperate with the channel faces in producing frusto-conical tips, means for shifting said movable opposed members in unison to carry said channel faces to position to alternately coöperate with said primary and secondary blades, and means for
55 operating said upper shear blade and folding blades.

17. A machine for applying celluloid tips to strip fabric, comprising folders for wrapping the celluloid around the fabric, means for supplying a solvent to soften the entire inner surface of the celluloid before completion of the wrapping operation and means for compressing the celluloid upon the strip and condensing both the strip and the wrapped celluloid while the inner surface of the latter is softened, to force some of the celluloid into the fibers of the strip.

18. A machine for applying celluloid tips to strip fabric, comprising folders for wrapping the celluloid around the fabric, means for supplying a solvent to soften the entire inner surface of the celluloid before completion of the wrapping operation, means for compressing the celluloid upon the strip and condensing both the strip and the wrapped celluloid while the inner surface of the latter is softened to force some of the celluloid into the fibers of the strip, and means for severing both the celluloid and the condensed fabric wrapped within it.

In testimony whereof I have affixed my signature, in presence of two witnesses.

ERNEST A. GALLISON.
